UNITED STATES PATENT OFFICE.

OTTO E. BORNHAUSER AND JOHN EDWARD HERMAN, OF SANDUSKY, OHIO, ASSIGNEES
TO THE WAGNER REFRIGERATION COMPANY, OF SANDUSKY, OHIO.

REFRIGERATING APPARATUS.

1,255,505.

Specification of Letters Patent. Patented Feb. 5, 1918.

Application filed December 15, 1917. Serial No. 207,348.

To all whom it may concern:

Be it known that we, OTTO E. BORNHAUSER and JOHN EDWARD HERMAN, of Sandusky, in the county of Erie and State 5 of Ohio, have invented certain new and useful Improvements in Refrigerating Apparatus, of which the following is a specification.

Our invention relates to refrigerating apparatus of the absorption type, and more particularly to refrigerating apparatus of the intermittent absorption type, wherein an ammonia liquid container, termed generator-absorber, acts alternately as a generator 10 and as an absorber, being subjected, while acting as an absorber, to the action of cooling water, and on the other hand being heated while acting as a generator.

Our invention has reference mainly to 20 the means for controlling the application of the heating and cooling means to the generator; to the means for controlling communication between the generator-absorber, and the ammonia liquid receiver; and to 25 the means for controlling the temperature of the refrigerator wherein the liquid ammonia from the liquid receiver expands as a gas with consequent cooling effect. And our invention consists in certain improvements 30 for these purposes which can best be explained in connection with the accompanying drawings, forming part of this specification, to which reference will now be made for a better understanding of the invention.

In said drawings:

Figure 1 is a side elevation of so much of the refrigerating apparatus as is needed for the purposes of explanation.

40 Fig. 2 is a side elevation of the same at right angles to the plane of elevation in Fig. 1. In these figures portions of the shell of the generator-absorber are broken away to expose the interior parts, and portions of the mechanical devices are in section.

Fig. 3 is a detached view in sectional elevation of the diaphragm check valve which automatically controls communication between the generator-absorber and the liquid receiver, or rather between the generator-absorber, and the condenser in which the gas received from the generator-absorber, when acting as a generator, is received and con-

densed and from which it flows in liquid form to the receiver.

Fig. 4 is a sectional side elevation on enlarged scale of the hydraulic diaphragm and associated devices for operating the gas and water valves which control the supply of 60 cooling water and gas to the generator-absorber.

Fig. 5 is a plan of the valve box which contains the valves for controlling the supply of water to the hydraulic diaphragm. 65

Fig. 6 is a sectional elevation on an enlarged scale of the refrigerator and refrigerating chamber associated with the apparatus of Figs. 1 and 2, showing the details of the thermostatically governed diaphragm 70 for controlling the outlet from the refrigerator or expansion chamber.

Fig. 7 is a horizontal axial section detached of the screw valve and case in Fig. 6.

The apparatus shown in the drawings is 75 one wherein the valves which shut off and let on the heating and cooling media to the generator-absorber, according as the latter is acting as a generator or as an absorber, are controlled by a float in the liquid receiver, which rises and falls with the rise and fall of the level of the liquid in the receiver, the rising and falling movement being availed of to actuate mechanism by which the said valves are operated, as set 80 forth in the application of Otto E. Bornhauser Ser. No. 149,516 filed February 19, 1917 on which Letters Patent will issue of even date herewith. The improvements subject of our present application have indeed 85 been made with special reference to the needs of an apparatus of the character described in said Bornhauser's application, and are shown in our drawings in connection with an apparatus of that character. 90

A is the cylindrical shell of the generator-absorber, mounted in upright position on the base B, containing the burner B' (shown in dotted lines) for heating the generator-absorber when used as a generator. 100 Gas is supplied to the burner through a pipe b controlled by a valve or cock b', and a small burner b² supplied with gas from a suitable source is provided to furnish a pilot flame, as usual in devices of this character. 105

The generator-absorber A is surmounted by the ammonia liquid receiver C containing the float C', and surmounting the liquid

receiver C is a water jacketed condensing coil D communicating at one end *d* with the gas space within the generator-absorber, and at the other end *d'* with the liquid receiver C, as usual in apparatus of this kind—thus arranging these parts of the apparatus in exceedingly convenient and compact form.

The water for the cooling water circulating system of the apparatus is supplied through a pipe E leading from a suitable source of water supply. The water thus supplied enters first a cooling coil E' in the liquid receiver C, and passes thence successively through the annular space between the external water jacket and internal ammonia pipe of the condenser coil D, and the dehydrating coil E² in the gas space within the generator-absorber to the discharge pipe E³, in which is located a valve e', automatically operated to open and close concurrently with the opening and closing of the gas supply cock or valve b'. In a by-pass from the water discharge pipe E³, is a cooling coil E⁴ located in the ammonia liquid containing portion of the generator-absorber A, the inlet end of said coil being connected to the pipe E³ at e² above the valve e', and its outlet end e³ connected to the discharge pipe E³ below the valve e'. Under this arrangement the coil E³ will be included in the water circulating system when the valve e' is closed (which is when the generator-absorber is acting as an absorber) and will be cut out of the circuit when the valve e' is open (which is when the generator-absorber is acting as a generator).

A spring closing thermostatically controlled valve e of any suitable type in the water supply pipe E is arranged to close whenever and so long as the temperature of the ammonia liquid in the generator-absorber falls below a certain degree, with a view to avoid the use of water during the period of quasi inactivity of the generator-absorber, while the liquid receiver is giving up its contents to the refrigerator. The thermostatic device for holding the valve e open against the stress of its closing spring whenever and so long as the temperature of the ammonia liquid in the generator-absorber is above a certain degree is indicated in full and dotted line at e^x.

As thus far described the apparatus does not differ essentially from the apparatus described and claimed in the aforesaid application of Otto E. Bornhauser Ser. No. 149,516.

We come now to those portions of the apparatus in which our present invention is embodied.

The hydraulic diaphragm for operating the gas valve or cock b' and the water valve e', is located above and in convenient prox-

imity to said valves, in which position it is supported by a bracket f^x laterally projecting from the shell of the generator-absorber A as shown in Fig. 1. It consists of a case F of cylindrical form between the flanged meeting faces of the top and bottom sections of which is held the diaphragm f, of rubber or other proper material, the rim of which is inserted and clamped between the flanged meeting faces of the two sections of the case F which are tightly bolted together. The bottom section f' of the case (preferably made of brass) is dished in shape as seen in Fig. 4, and has in it an axial circular opening f², above, and concentric with, which is a disk f³ secured upon the under face of the diaphragm and of sufficiently greater diameter than the opening f² to overlap the edges of the latter when the diaphragm is distended and depressed as shown in Fig. 4. The upper section f⁴ of the case is also dished or concavo-convex in shape, having in its top a tubular connection f⁵ with the valve box G, as shown. In the top of the valve box is an inlet connected with the water supply pipe E by a branch g, at a point in advance of the thermostatically controlled valve e, so that it shall be unaffected by the opening or closing of said valve; and in the bottom of the valve box is an outlet connected by a branch g' to the water discharge pipe E³, as shown more particularly in Fig. 1. The inlet to the valve box as seen in Fig. 4 is controlled by a valve g², and the outlet therefrom is controlled by a valve g³. These valves are pivoted to the opposite ends of an arm g⁴ mounted between its two ends upon, and secured fast to, a rock shaft or spindle g⁵, projecting from the outside into the interior of the valve box through a bearing g⁶ in which it is supported and can rock, the arrangement being such that when the inlet valve is open the outlet valve will be closed and vice versa.

The rocking movement of the spindle g⁵ is derived from the float C' within the liquid receiver C. For this purpose, the outer end of the spindle g⁵, has fastened to it a radial arm g⁷ having a pin and slot connection with the lower end of a connecting rod g⁸, as shown in Fig. 1 (the slot being in the rod g⁸), said connecting rod g⁸, being pivotally connected at its upper end to the end of a crank arm c' fast on the outer end of a rock shaft c, which extends into the interior of the liquid receiver C through a bearing sleeve c² provided for that purpose in the wall of the liquid receiver, and is provided at its inner extremity with a radial rod or arm c³, which is jointed at its other extremity by suitable means to a standard c⁴ on the top of the float C'. The parts of this connecting mechanism between the rock shaft or spindle g⁵, to which the valves g², g³

*g*³ are connected, and the float are so proportioned and adjusted, and the length of the slot in the lower end of the connecting rod *g*⁸ is such, that the two valves will be shifted at the time the float in its rise or descent reaches the predetermined limit of its movement. When the float *C'* is in its lowest position, (in which it is shown in dotted lines in Fig. 2) the inlet valve *g*² 10 will be open, and the outlet valve *g*³ will be shut. Under these conditions water from the source of water supply (which should be under an adequate head, say 51 lbs. or thereabout to the square inch) flows 15 through the inlet branch *g* into the valve box *G*, and thence into the water chamber in the case *F* above the diaphragm *f*, thus distending and depressing the diaphragm as far as permitted by the lower dished case 20 section *f'* and the disk *f*³ on the underside of the diaphragm. The parts are shown in this position in Fig. 4. When however the valves *g*², *g*³ are shifted so as to close the inlet valve and open the outlet valve, the 25 inlet branch *g* to the valve box *G* is closed thus shutting off the water supply, and the outlet branch *g'* is opened, thus relieving the water pressure from above the diaphragm, and permitting the water from the 30 box to escape and pass off to the discharge pipe *E*².

This arrangement is availled of as follows to operate the gas and water valves *b'*, *e'*.

35 To the under side of the annular rim of the hydraulic diaphragm case *F*, and diametrically opposite one another, are secured two brackets *h*, in each of which is pivoted between its ends a lever *h'*, the inner opposite ends *h*² of which are upturned and project up through the central opening *f*², in the bottom section of the case *F*, against the disk *f*³ attached to the under face of the diaphragm *f* above, and are held against 40 said disk with yielding pressure by means of a tension spring *s* stretched between and connected by its ends to the downwardly extending third arms *h*⁴ of the levers *h'*. The exterior opposite ends of the two levers 45 are connected, the one to the water valve *e'* and the other to the gas valve or cock *b'*, by connecting rods *h*⁴ and *h*⁵ respectively as shown in Fig. 1.

Under this arrangement, whenever and so 55 long as the inlet valve *g*² is open and the outlet valve *g*³ is closed, water will enter the valve box and diaphragm chamber in the case *F*, and by its head will depress the diaphragm *f* against the resistance of the 60 spring *s*, with the effect of rocking the levers *h'* in a direction to open the gas and water valves *b'*, *e'*, thus admitting gas to the burner *B'*, and cutting out from the cooling water circulating system the cooling coil *E*⁴ 65 in the liquid containing portion of the gen-

erator-absorber, as indicated in Figs. 1, 2 and 4, the float *C'* in the liquid receiver *C* being in its lowest position. On the other hand, when the ammonia liquid has accumulated in the liquid receiver in sufficient 70 quantity to raise the float to a predetermined limit, the inlet and outlet valves *g*², *g*³ will be shifted to close the inlet, and open the outlet, thus shutting off water from the diaphragm chamber and opening up communication between it and the discharge pipe *E*³, and consequently relieving the water pressure on the diaphragm *f*, and permitting the levers *h'* to be pulled by the spring *s* in a direction to close the gas and 75 water valves, *b'*, *e'*, with the effect of shutting off the gas from the burner *B'* and including the cooling coil *E*⁴ in the water circulating system. 80

This arrangement for controlling the heating and cooling means for the generator-absorber, which is available wherever water supply under a certain head or pressure can be had, is effective in action, and free from complication. 85

In lieu of the ordinary check valve between the condenser and the gas-space of the generator-absorber for preventing back flow from the condenser, we prefer to employ the diaphragm check valve arrangement indicated in Fig. 2 and shown on enlarged scale and in detail in Fig. 3, which we have found to be sensitive and effective in operation for this purpose. 90

From the gas space within the generator-absorber, a dehydrator tube *J*, open at its inner end and closed at its outer end, passes through the shell of the generator-absorber, with a downward inclination from its outer to its inner end, so that whatever liquid 105 it may condense will flow back and drop into the body of liquid in the lower portion of the generator-absorber. The upper terminal of the dehydrating coil *E*², as shown in Fig. 2, passes out from the shell of the 110 generator-absorber longitudinally through the dehydrator tube *J*, before connecting through the pipe *e*⁴ with the water jacket of the condenser coil, thereby further cooling the gas in the dehydrator tube and aiding in the precipitation and separation of any water vapor that may be mixed with it. The valve *e*⁵ on the pipe *j* is a hand-operated valve to be used only in case of repair to the 115 generator-absorber. 120

Interposed between the dehydrator tube *J* and the condenser is the diaphragm check valve arrangement, consisting of a diaphragm case *I* divided horizontally into two chambers by a diaphragm *i* of suitable elastic material. The lower chamber has an inlet *i*² communicating with the pipe *j* leading from the gas space of the generator-absorber, and an outlet *i*³ leading through pipe *i*⁴ to the inlet end *d* of the con- 125 130

4
denser D, and controlled by a check valve i^5 , attached to the under face of, and moving with, the diaphragm i . The upper chamber has an inlet i^1 , communicating through 5 a branch pipe i^2 , with the pipe i^3 that leads from the lower chamber to the inlet d of the condenser; and said chamber also contains a spring s' , which presses upon the diaphragm i in a direction to close the outlet i^2 in the lower chamber controlled by the 10 diaphragm check valve i^5 . Under this arrangement, whenever and so long as the pressure in the generator-absorber is above the pressure in the liquid receiver combined 15 with that of the spring (which is during the distilling period) the diaphragm i will thereby be forced upward, carrying with it the diaphragm check valve i^5 , and thus opening outlet i^2 , and allowing gas to pass 20 out therethrough from the lower chamber whence it is conducted through pipe i^3 to the inlet end d of the condenser D, and thence in liquid form to the liquid receiver C.

25 When the latter is filled with liquid ammonia to the required height, and gas, as before explained, is consequently cut off from the burner, the pressure in the generator of course begins to drop. But by the 30 time the generator pressure has dropped to receiver pressure, the superior pressure from above on the diaphragm due to the independent action of the spring s' , will have depressed the diaphragm sufficiently to have 35 correspondingly depressed the diaphragm check valve i^5 to close the outlet i^2 through which the generator communicates with the receiver; and further reduction of pressure after the valve has thus closed, will cause 40 the now superior pressure in the receiver, to act on the diaphragm from above, in conjunction with the spring, to hold the diaphragm check valve tightly and securely closed against the back flow of any gas from 45 the receiver to the generator-absorber.

It remains to describe the means for controlling the temperature of the refrigerator which is associated with the apparatus thus far described, and is shown separately, and 50 to a large extent diagrammatically in Figs. 6 and 7.

In Fig. 6 is shown more or less schematically so much of a refrigerator 84 of any usual or approved type—such for example 55 as may be used in households or in hotels or the like—as needed to illustrate this portion of our improvements. In the ice chamber 85 of said refrigerator are located the devices by which refrigerating action is had, 60 comprising the casing 86 having at or near its bottom an inlet pipe 94, leading from the bottom of the liquid receiver C (Fig. 2), and at the top an outlet pipe 101, leading back to the generator-absorber which it enters at a point below the level of the liquid

therein, and discharging into the generator-absorber at that point through a perforated pipe section 100—suitable check valves 102, 103 being provided in the pipe 101 to prevent back pressure from the generator-absorber. These parts of the refrigerator and its connections with the liquid receiver and the generator-absorber, are the same as illustrated and described in the said Bornhauser application Serial No. 149,516, and are identified by like reference characters. 75

The inlet pipe 94 opens into a valve case k projecting laterally through the wall of the casing 86, into the interior of the same, and having its discharge passage k' , controlled 80 by a screw valve k^2 , provided with a radial operating arm k^3 , connected by a link connection k^4 , to the bottom of the float 93, within the casing 86. The valve k^2 , is actuated to open or close according as the float 85 falls or rises and they operate to maintain a constant level of ammonia in the chamber 86, thus drawing ammonia from the liquid receiver C only as rapidly as the ammonia expands in casing 86, the evaporated and 90 expanded ammonia returning through the pipe 101 to be re-absorbed by the liquid in the generator-absorber. We prefer this screw valve arrangement to that shown for a similar purpose in said Bornhauser's application Ser. No. 149,516, for the reason 95 that it is more certain in action and less liable to clog.

To control the temperature in the refrigerating chamber 85, we interpose in the outlet pipe 101, which leads the vapor from the expansion chamber or casing 86, back to the generator-absorber, a thermostatic diaphragm valve device. This device, located in the refrigerating chamber 85, comprises 100 a valve body or case L interposed in the outlet pipe line 101 as shown and containing a valve seat l' , and a vertically reciprocating valve l , the stem of which passes down and out through a stuffing box l^2 , and has on its 105 projecting lower end a disk l^3 , held in yielding contact with a diaphragm m of suitable elastic material, by an expansion spiral spring s^2 , encircling the valve stem and confined between the head of the stuffing box l^2 , and a nut l^4 on the screw threaded portion of the stem. The diaphragm closes the 110 top of a chamber formed in the dished or concavo-convex receptacle M, which is connected to a flask m' beneath it, by a tube m^2 . The device as a whole is connected to the 115 valve body L by the diaphragm ring or annulus N, between which and the annular rim of the receptacle M below the diaphragm m is clamped, said ring N being rigidly connected to and suspended from the valve body L, by an arch consisting of diametrically opposite side members N' formed integrally with or otherwise made fast to the ring N, and extending upwardly and bend- 120 125 130

ing inwardly toward their upper ends to join the coupling ring N^2 with which they are rigidly connected. The coupling ring is internally screw threaded, and is screwed upon 5 that portion of the downwardly projecting neck of the valve body L through which the valve stem plays that is above the stuffing box l^2 , said portion being externally screw threaded for that purpose.

10 The chamber M , the flask m' and the tubular connection m^2 , are full up to the diaphragm m with any suitable liquid having a high co-efficient of expansion, as for example alcohol. When temperature in the 15 cooling or refrigerating chamber is above a predetermined required point the liquid expands sufficiently to force the diaphragm upward with sufficient force to raise the valve l from its seat against the opposing 20 stress of the spring s^2 , thus allowing the expanded ammonia gas in expansion chamber 86 to escape and pass back through pipe 101 to the generator-absorber, where it will be absorbed. On the other hand when the 25 temperature in the cooling chamber 85 drops below the predetermined required point the liquid in the chamber M and flask contracts, and allows the valve to seat itself through the action of spring s^2 , thus closing the outlet 30 from the expansion chamber 86, and setting up a pressure in said chamber which prevents or retards the evaporation of the ammonia, and the reduction of temperature consequent upon such evaporation. Upon 35 the rise of temperature to the proper degree, due to the checking of the evaporation, the thermostatic valve will again open. In this way it is practicable to maintain a substantially uniform temperature in the refriger- 40 ator, it being easier to thus handle the ammonia in gaseous form than in liquid form as at the ammonia liquid inlet to the refrigerating chamber.

The general scheme of operation of the 45 apparatus in which our improvements are incorporated has been indicated in the foregoing specification and does not require further elaboration here.

In conclusion we desire it to be understood that we do not claim broadly the including of the cooling coil and the generator-absorber in a by-pass from the cooling water circulation system of the apparatus which is thrown into and out of circuit with 50 that system, according as the generator-absorber is acting as an absorber or as a generator, by means responsive to variations in the level of ammonia liquid in the liquid receiver, inasmuch as the same is the subject, 55 among other things, of the aforesaid Born- hauser application No. 149,516, on which Letters Patent will issue of even date here- with. Nor do we claim broadly the use of a thermostatic device at the outlet of the 60 expansion chamber of a refrigerating ap-

paratus for the purpose of controlling and keeping uniform the temperature within the cooling chamber.

On the other hand, having described our improvements and the best way now known to us of carrying the same into practical effect, we desire it to be understood that we do not limit ourselves strictly to the structural details hereinbefore set forth in illustration of our invention, since manifestly the same can be varied considerably without departure from the spirit of the invention; but what we claim as new and desire to secure by Letters Patent is:

1. In a refrigerating apparatus of the intermittent absorption type, the combination with the generator-absorber, the condenser, the ammonia liquid receiver, a burner and gas supply therefor for heating the generator-absorber, a cooling water circulating system, and a cooling coil in the generator-absorber included in a by-pass from said system, of valves for controlling the gas supply to the burner, and the water supply to the by-pass including the cooling coil; a 80 hydraulic diaphragm and chamber closed by said diaphragm; means responsive to variations in the level of the ammonia liquid in the receiver for admitting water under pressure to, and discharging it from, the 85 hydraulic chamber; and connections between the gas and cooling coil valves and the hydraulic diaphragm whereby the opening and closing of said valves is controlled by the movements of said diaphragm. 100

2. In a refrigerating apparatus of the type specified, the combination with the generator-absorber, the condenser and the receiver, of a diaphragm check-valve device comprising essentially a diaphragm case, a 105 diaphragm dividing the space within the diaphragm case into two chambers, the one chamber having an inlet connected with the gas space of the generator-absorber and an outlet connected to the inlet end of the condenser, and containing a check valve secured to and moving with the diaphragm in position to control said inlet, the other chamber having an inlet, which has a common connection with the outlet in the first mentioned chamber to the inlet end of the condenser, and a spring which tends to force the dia- phragm in a direction to close the check valve upon the inlet communicating with the gas space of the generator-absorber, 120 these parts being arranged for joint operation substantially as and for the purposes hereinbefore set forth.

3. The combination with the generator-absorber, the ammonia liquid receiver, the 125 refrigerating or cooling chamber and the expansion chamber within the same having an inlet communicating with the liquid receiver and a float operated valve for controlling said inlet, and an outlet communi- 130

cating through suitable connections with the generator-absorber, of a thermostatic dia-
phragm check valve device for controlling
said outlet, comprising essentially a check
5 valve spring-pressed in a direction to nor-
mally close said outlet; a receptacle con-
taining a body of liquid having a high co-
efficient of expansion; and an elastic dia-
phragm closing the receptacle, and tend-

ing when expanded to move the valve in a 10
direction to open it against the stress of its
opposing spring, these parts being arranged
together for joint operation substantially as
and for the purposes hereinbefore set forth.

In testimony whereof we affix our signa- 15
tures.

OTTO E. BORNHAUSER.
J. EDWARD HERMAN.
